Fig. 1

Fig. 2

Fig. 3

FIG. 1 is a perspective view of a bird feeder showing my new design;

FIG. 2 is a left side elevational view; and

FIG. 3 is a rear elevational view.

The fragmentary hexagonal design on the central rectangular-shaped portion of the front and rear elevational views represents hexagonal embossing on a window which extends throughout the rectangular-shaped area.

I claim:

The ornamental design for a bird feeder, as shown and described.
